tion, operation and advantages of the invention will be apparent. Modifications and changes in details of construction are contemplated within the spirit of the invention as claimed.

Having described the invention, what is claimed as new is:

1. An advertising folder comprising a sheet adapted to be folded on a horizontal fold line to provide an upper portion and a lower portion, the lower portion being provided with a single horizontal slit in spaced relation to said fold line, and a display device comprising a strip folded transversely intermediate its ends and having one end extended forwardly through said slit and provided on its front face with display matter, the other end of said strip being attached to the back of the upper portion so that when the sheet is unfolded said one end of the strip is projected to a position in front of said upper portion of the sheet to reveal said display matter, and when the sheet is folded said one end of the strip is retracted with its major portion positioned behind said lower portion of the sheet.

2. An advertising folder comprising a sheet adapted to be folded on a horizontal fold line to provide an upper portion and a lower portion, the lower portion being provided with a single horizontal slit in spaced relation to said fold line, and a display device comprising a strip folded transversely intermediate its ends and having one end extended forwardly through said slit and provided on its front face with display

matter, the other end of said strip being attached to the back of the upper portion so that when the sheet is unfolded said one end of the strip is projected to a position in front of said upper portion of the sheet to reveal said display matter, and when the sheet is folded said one end of the strip is retracted with its major portion positioned behind said lower portion of the sheet, and a guide strip attached to the back of said lower portion of the sheet, the portion of the strip adjacent its fold slidably extending under said guide strip.

3. A folder according to claim 2 wherein said strip has a terminal portion extending through said slit when the sheet is folded.

4. A folder according to claim 2 wherein said strip has a terminal portion extending through said slit when the sheet is folded, and those portions of the strip on each side of and adjacent to the fold line thereof are slidably mounted between said guide strip and the adjacent portion of said lower portion.
